ROLL GLUE SPREADER

Harry G. Francis, Rushville, Ind., assignor to
Chas. E. Francis Co., Rushville, Ind., a Corpora-
tion of Indiana

Application January 20, 1930. Serial No. 421,934

2 Claims. (Cl. 91—51)

My invention is concerned with machines for spreading glue or other adhesive, which machines embody a roll that dips into a glue-pan and that may be rotated in contact with the 5 surface of the board or other article upon which glue is to be spread. One such machine is shown in my prior Patent No. 1,661,174.

In such prior patent, the pan which contained the glue into which the lower roll dipped was 10 mounted in fixed position relative to the roll, and it was necessary at all times to maintain the glue-level above the lowest point of the roll. This precluded the possibility of using all the 15 glue in the pan unless the roll was placed very close to the pan-bottom; and if it were so placed, the roll filled such a large proportion of the tank that the glue-capacity thereof was greatly diminished.

It is the object of this invention to produce a 20 roll glue-spreading machine in which the glue or other adhesive in the pan may be substantially all used, and to do this in such a manner that the capacity of the glue pan is not decreased to an undesirable extent.

25 I accomplish my object by adjustably supporting the glue-pan in such a manner that it may be adjusted vertically with reference to the roller which dips into the glue it contains.

The accompanying drawing illustrates an em- 30 bodiment of my invention. Fig. 1 is a partial front elevation of a double-roll glue-spreading machine with parts thereof broken away to illustrate the construction more clearly; Fig. 2 is an end elevation of the machine; and Fig. 3 is a section on the line 3—3 of Fig. 1 illustrating details of construction.

The glue-spreading machine illustrated in the drawing is more clearly shown and described in my prior Patent No. 1,661,174. This is illus- 40 trated merely by way of example, as my invention is applicable to other forms of glue-spreading machines.

In the machine illustrated in the drawing, a 45 frame 10 supports two rotatable rolls 11 and 12 disposed one above the other. A glue-pan 13 is mounted below the roll 11 in such a position that the roll can dip into a supply of glue or other adhesive in the pan. Associated with the upper roll 12, there is also a glue-pan 14 by 50 means of which glue is applied to the face of such roll. The boards or other objects to which glue is to be applied are passed between and in contact with the two rolls, which pick up glue from the two pans respectively associated with 55 them and apply it to the boards as they pass

between the rolls. Scraper or "doctor" rolls 11' and 12' associated respectively with the rolls 11 and 12 limit the amount of glue which is applied to boards passing between the rolls.

As previously stated, the present invention 60 contemplates that the glue-pan 13 associated with the lower roll 11 will be vertically adjustable. One method of accomplishing this result is shown in the drawing, where the pan 13 is shown as provided at each end with a vertical 65 support 15. The supports 15 are slidably received within suitable guides 16 mounted on the frame 10 of the machine. By providing means for raising and lowering the supports 15, the glue-pan 13 can be raised or lowered as desired. 70

The means shown in the drawing for vertically moving the supports 15 comprises a rock-shaft 20 which extends horizontally generally parallel to the rolls 11 and 12 and offset from the supports 15, as is clear from 75 Fig. 2. Adjacent each of the supports 15, we mount on the rock-shaft 20 an arm 21 which extends outwardly from the shaft to a point beneath the associated support 15. Desirably, the arms 21 engage the supports 15 through rollers 80 22 mounted on the outer ends of the arms 21. It will be evident that as the shaft 20 is rocked in a counter-clockwise direction (Fig. 1) the glue-pan 13 and supports 15 will be raised; while if the shaft 20 is rocked in the reverse direction, 85 the glue-pan is permitted to drop under the influence of gravity.

For the purpose of rocking the shaft 20, I may secure to it, preferably near one end, an operating arm 25 which, at its outer end is 90 slotted to receive slidably a block 26, the sides of the slot forming bearing surfaces for the block. The block 26 has a central hole by means of which it is mounted on a cylindrical projection 27 of a nut 28 which in turn is 95 mounted upon an adjusting screw 29. The adjusting screw is rotatably supported in fixed axial position as by means of bearing-blocks 30 secured to the frame 10. The outer end of the screw 29 may be formed in square or other non- 100 circular cross-section for the reception of a wrench or operating handle by means of which the screw may be rotated.

It will be apparent that the vertical position 105 of the glue-pan 13 may be controlled by means of the screw 29. As shown in the drawing, the glue-pan is elevated to such a point that the associated glue-spreading roll 11 nearly touches the pan-bottom. The pan-bottom is conveniently convex outwardly with its lowest point 110

immediately beneath the roll 11. By this arrangement, substantially all the glue in the pan 13 may be used.

When it is not desired to use all the glue in the pan 13, the pan may be lowered to decrease the proportion of the roll which lies in the pan, and thereby to increase the capacity of the pan. Such lowering movement is accomplished by rotation of the screw 29 which results in movement of the nut 28 to the right (Fig. 2) and rocks the shaft 20 in a clockwise direction. This lowering of the glue-pan not only results in increasing its capacity but also makes it readily accessible for cleaning.

My invention is not limited in its application only to machines of the type described, as it may be embodied in any machine in which there is incorporated a spreading or applying roll which dips into a supply of glue or other adhesive in the pan.

I claim as my invention:

1. In combination, a frame, an adhesive-spreading roll rotatably supported therefrom on a substantially horizontal axis, a pan located beneath said roll and adapted to contain a supply of adhesive into which the roll may dip, guiding means supporting said pan for vertical

movement toward and away from said roll, a shaft, means operatively interconnecting said shaft and pan whereby rotational movement of said shaft will produce vertical movement of said pan, and control means for adjusting said shaft, said control means including a screw rotatably mounted in said frame.

2. In an adhesive-spreading machine having a frame and an adhesive-spreading roll rotatably mounted on a substantially horizontal axis in said frame, a pan located beneath said roll and adapted to contain a supply of adhesive into which said roll may dip, said pan being movably mounted in said frame for movement toward and away from said roll, a shaft mounted in said frame, means operatively interconnecting said shaft and pan whereby rotational movement of said shaft will produce vertical movement of said pan, an operating arm secured to said shaft, a pivot block slidably mounted in said arm, an operating screw rotatably mounted on said frame, and a nut associated with said screw and adapted to move therewith when the screw is rotated, said nut being connected to said pivot block.

HARRY G. FRANCIS.
